CZECHO-SLOVAKIA.

SCUTCHING MACHINE.

1,405,990.

Specification of Letters Patent. Patented Feb. 7, 1922.

Application filed November 18, 1919. Serial No. 338,934.

(GRANTED UNDER THE PROVISIONS OF THE ACT OF MARCH 3, 1921, 41 STAT. L., 1313.)

To all whom it may concern:

Be it known that I, IGNAC ETRICH, a subject of the Czechoslovak Republic, residing at Oberaltstadt, near Trautenau, Bohemia, have invented certain new and useful Improvements in Scutching Machines, (for which I have filed applications in Austria, July 29th, 1916, Patent No. 77,212 issued; Hungary, December 30th, 1916; Germany, August 20th, 1916, Patent No. 310,654 issued; Holland, October 10th, 1916; Great Britain, November 8th, 1916, Patent No. 108,452/16027 issued; Belgium, June 15th, 1918; France, August 27, 1919; Sweden, September 8th, 1919;) and I do hereby declare the following to be a full, clear, and exact description of the invention, such as will enable others skilled in the art to which it appertains to make and use the same.

20 This invention has for its object to provide an improved machine for the continuous scutching of flax, hemp or the like.

It has been proposed to use in scutching and similar machines a plurality of rings adapted to hold the stricks or leaves at both ends alternately while the other ends of such stricks have been worked upon, means being provided to transfer the stricks in a vertical or horizontal position from one of such rings to the next following.

According to this invention the bent or broken stalks are placed in handfuls or stricks by hand upon, and fixed with one end into a horizontal ring which feeds the stricks over guide plates to a scutching apparatus. After passing through this scutching apparatus the stricks are placed automatically upon and fixed at their other ends into a second and similar ring which conveys them to a second scutching apparatus which treats the ends of the stricks that have been fixed in the first ring. The stricks coming from the second ring may be placed upon and fixed into a third and a fourth ring, and generally any desired number of pairs of rings in succession, so that the said stricks are alternately treated at each end.

60 The manner in which this invention is to be performed will now be more particularly described with reference to the accompanying drawings which illustrate by way of example a practical construction of an improved machine according to this invention. In these drawings:

Figure 1 is a plan of a constructional form of a continuously operating scutching machine according to this invention;

Figure 2 is a section on the line A—A of Figure 1;

Figure 3 is a plan of a detail.

Figure 4 a side elevation partly in section of the delivery end of the endless cords and the chain of blocks.

Figure 5 is a front elevation on a slightly enlarged scale.

The stricks or handfuls of stalks of flax, hemp or the like which have passed between the breaking rolls pass on to a table *n* whence the workman takes them and places them upon the first ring *R'*. In order to ensure that the stricks shall be placed as nearly as possible radially to the ring, a conveyer band *e* is provided (below the latter) which takes with it the free ends of the stricks; this conveyor band travels in proximity to the charging place in the same direction as the periphery of the ring. The workman pushes one end of the stricks under endless elastic cords *s* which run over small wheels *l* and which pass along grooves *r* in the upper side of the ring *R'*, and are pressed forcibly into these grooves by an endless chain of blocks *K*, so that the stricks are held firmly and securely between the ring and the cord.

85 The endless chain of blocks *K* runs over two guides of which the upper one consists of an arc-shaped guide channel *c'* and the lower one consists of small wheels *c* which are mounted in a freely rotatable manner upon levers *h* that are under the pressure of springs *a*; the small wheels *c* form an arc concentric to the ring. The levers *h*, as well as the upper guide channel *c'* for the chain of blocks, are mounted above the ring *R'* 90 in such a manner that the chain of blocks has its lower stretch that runs under the pressure wheels *c*, pressed against the upper surface of the ring as it follows its periphery, whilst the upper stretch of the 100 chain of blocks follow likewise the periphery of the ring and returns over the guide channel *c'*. The ring *R'* is slowly rotated by any suitable means, for instance by means of pinions which are driven from a suitable counter gearing and engage in the toothed underside of the ring *R'*.

105 By means of this apparatus, the stricks

which are pushed by the workman underneath the cords s are drawn by the latter under the chain of blocks and are clamped in the channels c' , whilst their free ends 5 pass over guide plates e' , whereby the stricks are held horizontally and in this position are conveyed over fluted rolls to a scutching apparatus m , the construction of which does not form part of the present invention. During the passage of the stricks through the scutching apparatus, one longitudinal half of the stricks is treated. After 10 leaving the scutching apparatus the stricks pass over guide plates e' to conveyor rollers f which deliver them to a conveyor band e' whereby they are conveyed over a second ring R^2 which has conveyed over a second 15 structure as the ring R' . The position of the conveyor rollers f and the conveyor band e' , as likewise their velocities, are made such that the stricks will place themselves with their ends that have been treated in the scutching apparatus m approximately radial to the second ring R^2 and will be gripped 20 by the cords s and the block chain K of the said second ring, whilst the other ends of the stricks are still clamped to the first ring R' . As the two rings R' , R^2 continue to 25 rotate, the stricks are carried along gripped at both ends and are finally released from the ring R' owing to their ends which are clamped to this ring, passing away from 30 under the second guide wheel l of the cords s .

Then the stricks are conveyed from the 35 second ring R^2 over the guide plate e' in a horizontal position to the second scutching apparatus m' where their ends that have been clamped in the first ring are now treated.

40 If one treatment of each end of the stricks is thought sufficient, the stricks are laid aside after passing under the second guide wheel of the cords s of the second ring R^2 . If it is desired that each end of the stricks shall 45 be subjected to more than one treatment, then one or more further pairs of rings are added to the pair of rings R' , R^2 ; the transference of the stricks from one ring to the next one taking place automatically in the 50 same manner as is above described with reference to the transference from ring R' to the ring R^2 . Then the two ends of the stricks are treated alternately.

Owing to the circumstance that the 55 stricks are subjected to a continuous treatment, the efficiency of the machine is very high and owing to the circumstance that the stricks are presented horizontally to the scutching devices, the cleaning is far more 60 thorough than when the stricks are treated vertically.

Moreover, the repeated treatment of each end of the stricks (when more than one pair of rings is employed) enables the clean-

ing process to be completed in one operation and thus saves the fibres.

The arrangement of these parts at the drawing in end is in all respects similar to that at the delivery end.

The endless chain of blocks consists of a 70 series of blocks K suitably hinged the one to the other. In the lower or working stretch the blocks are guided along that part (substantially one half) of the wheel moving towards the next following wheel by 75 guide rollers c journaled at the ends of levers forming a series concentric to the ring, say R' and fulcrumed on a rail h' rigidly held in a fixed relation to the ring, say R' and this series of levers is acted 80 upon by suitable springs a . The upper or idle stretch of the chain of blocks is guided above the lower stretch by a channel c' Figure 2. The chain of blocks K passes at the 85 ends of the series of levers h round guide wheels K' . These wheels are situated in vertical planes substantially tangential to the ends of the arc of the circle occupied by the levers h , and are free to revolve on journals rigidly held in a fixed relation to the 90 ring, say R' .

The rings are provided with concentric 95 grooves r on their upper face and the chain of blocks K and the series of the levers h and their guide rollers c are so arranged 100 that they follow the grooves r in that part (substantially one half) of the ring, say R' moving towards the next following ring. Endless elastic cords s are so arranged that 105 their working stretches are forced by the working stretch of the endless chain of blocks K into that part of the grooves r which is under the guide rollers c of the lever h , while the idle stretches of the said cords s run above the rings; the endless 110 cords s are guided by grooved pulleys l adjacent to the guide wheels K' of the endless chain of blocks K and situated in vertical planes substantially parallel to the axes of the wheels K' or radial to the ring R' as 115 clearly shown in Figures 1, 4 and 5.

The operation is the following: The stricks are pushed between the elastic cords s and the ring, say R' at the drawing in end and as the ring continues to revolve and takes 115 with it by friction the working stretches of the cords s of the endless chain of blocks K the ends of the stricks are caught and firmly held between and move along with the ring past the series of levers h until the 120 stricks reach the delivery end of the series of levers h and the cords s where they are released.

Claims—

1. In a scutching machine the combination 125 of a plurality of horizontal rings arranged closely side by side, means for revolving such rings on their geometrical axes, adja-

- cent rings revolving in opposite directions, each of the rings being provided on its upper face with concentric grooves, endless elastic cords, the working stretch of which follows 5 that part of the grooves of their ring which moves towards the next following ring, means for guiding back the idle stretch of each elastic cord above its working stretch, means for continuously moving the elastic 10 cords of each ring and means for holding the working stretch of the cords against the grooves in its ring, the working stretch of such cords moving at the same speed and in the same direction as the part of the grooves 15 of its ring which these cords follow and adapted to hold stricks of the material to be scutched at one end in the said grooves whereby the said stricks are carried round by the rings, means for scutching the other 20 ends of the said stricks, while the latter are thus carried round and means for disengaging the first named ends of stricks from one ring and presenting them to and engaging them with the next following ring with the 25 other end of the stricks in a substantially horizontal plane and in a direction substantially radial to the latter ring.
2. In a scutching machine the combination of a plurality of horizontal rings arranged 30 closely side by side, means for revolving such rings on their geometrical axes adjacent rings revolving in opposite directions each of the rings being provided on its upper face with concentric grooves, elastic cords, 35 the working stretch of which follows that part of the grooves of their ring which moves towards the next following ring, means for guiding back the idle stretch of each elastic cord above its working stretch, means for 40 continuously moving the elastic cords of each ring and means for holding the working stretch of the cords against the grooves in its ring, the two last named means comprising an endless chain of blocks hinged the 45 one to the other, a series of weighted levers carrying rollers at one end, such rollers being adapted to bear on the blocks of the chain and being arranged in an arc of a circle concentric to and above the grooves in the 50 ring, the working stretch of the cords passing between the said rollers and along the grooves in the ring, means for guiding the working stretch of the endless chain of blocks into the space between the said 55 rollers and out of such space and back again whereby the working stretch of the said cords is moved at the same speed and in the same direction as the part of the grooves in the ring which these cords follow and adapted 60 to hold stricks of the material to be scutched at one end in the said grooves and to carry such stricks round with the rings, means for scutching the other ends of the said stricks, while the latter are thus carried 65 round and means for disengaging the first
- named ends of the stricks from one ring and presenting them to and engaging them with the next following ring with the other end of the stricks in a substantially horizontal plane and in a direction substantially radial to the latter ring.
3. In a scutching machine the combination of a plurality of horizontal rings arranged closely side by side, means for revolving such rings on their geometrical axes, adjacent 70 rings revolving in opposite directions, each of the rings being provided on its upper face with concentric grooves, endless elastic cords, the working stretch of which follows that part of the grooves of their ring which moves towards the next following ring, means for guiding back the idle stretch of each elastic cord above its working stretch, means for continuously moving the elastic 75 cords of each ring and means for holding the working stretch of the cords against the grooves in its ring, the working stretch of such cords moving at the same speed and in the same direction as the part of the grooves of its ring which these cords follow 80 and adapted to hold stricks of the material to be scutched at one end in the said grooves whereby the said stricks are carried round by the rings, means for scutching the other ends of the said stricks, while the latter are thus 85 carried round and a series of conveyor rollers and a conveyor band between the delivery end of the working stretch of the cords of one ring and the entering end of the working stretch of the cords of the next following 90 ring whereby the free ends of the stricks clamped in the former ring are transferred in a substantially horizontal plane and in a direction substantially radial to the entering end of the working stretch of the cords of the latter ring.
4. In a scutching machine the combination of a plurality of horizontal rings arranged closely side by side, means for revolving such rings on their geometrical axes adjacent 95 rings revolving in opposite directions each of the rings being provided on its upper face with concentric grooves, elastic cords, the working stretch of which follows that part of the grooves of their ring which moves towards the next following ring, means for guiding back the idle stretch of each elastic cord above its working stretch, means for continuously moving the elastic cords of each ring and means for holding the working stretch of the cords against the grooves in its ring, the two last named means comprising an endless chain of blocks hinged the 100 one to the other, a series of weighted levers carrying rollers at one end, such rollers being adapted to bear on the blocks of the chain and being arranged in an arc of a circle concentric to and above the grooves in the ring, the working stretch of the cords passing between the said rollers and along the grooves in the ring, means for guiding the working stretch of the endless chain of blocks into the space between the said rollers and out of such space and back again whereby the working stretch of the said cords is moved at the same speed and in the same direction as the part of the grooves in the ring which these cords follow and adapted 105 to hold stricks of the material to be scutched at one end in the said grooves and to carry such stricks round with the rings, means for scutching the other ends of the said stricks, while the latter are thus carried round and means for disengaging the first

in the ring, means for guiding the working stretch of the endless chain of blocks into the space between the said rollers and out of such space and back again, whereby the 5 working stretch of the said cords is moved at the same speed and in the same direction as the part of the grooves in the ring which these cords follow and adapted to hold stricks of the material to scutched at one end in the 10 said grooves and to carry such stricks round with the rings and a series of conveyor rollers and a conveyor band between the delivery end of the working stretch of the cords of one ring and the entering end of the

working stretch of the cords of the next following ring whereby the free ends of the stricks clamped in the former ring are transferred in a substantially horizontal plane and in a direction substantially radial to the entering end of the working stretch of the 20 cords of the latter ring.

In testimony whereof, I affix my signature in presence of two witnesses.

IGNAZ ETRICH.
